UNITED STATES PATENT OFFICE.

ROMAN B. BUKOLT, OF STEVENS POINT, WISCONSIN.

STEERING-POST MOUNTING.

Application filed August 19, 1926. Serial No. 130,253.

The invention relates to improvements in means for rotatably connecting steering posts of children's vehicles to body members, the object of the invention being to provide an exceptionally simple and inexpensive, yet an efficient and very desirable construction and arrangement for this purpose.

5 The invention is shown in connection with a three wheeled vehicle having pedals for 10 propelling it, but it is applicable also to vehicles of other types.

15 With the foregoing in view, the invention resides in the novel subject matter herein-after described and claimed, the description 20 being supplemented by the accompanying drawing.

Figure 1 is a side elevation of a child's vehicle embodying the invention.

Figure 2 is an enlarged longitudinal sectional view through the post mounting means.

Figure 3 is a vertical transverse section as indicated by line 3—3 of Fig. 1.

The numeral 5 on the drawing designates 25 a steering post at the front end of a seat board or body 6, the rear end of the latter being supported by wheels, one of which is shown at 7. The upper end of the post 5 is provided with a handle bar 8 while its lower 30 end is provided with a fork carrying a dirigible front wheel 9, said wheel in the present disclosure, being provided with pedals 10. The gist of the present invention is utilized 35 for establishing a connection between the steering post 5 and the body 6.

Two metal bars 11 have their upper ends transversely curved and secured against opposite sides of the post 5, at the lower portion of the latter, these transversely curved 40 bar ends being indicated at 12. These two ends extend approximately throughout the transverse circumference of the post 5 and form an effective metal covering therefor, and they are secured to the post by rivets 45 13. At the lower end of the post 5, the bars 11 are directed laterally outward as at 14 and then are extended downwardly to provide a fork for the wheel 9, and resting upon the portions 14, is a bearing collar 15 which 50 surrounds the post 5 and the bar ends 12.

Secured by rivets or the like 16 to the upper and lower side of the body 6, at the front end of the latter, are two bars 17 whose front portions project forwardly from said body 55 6 and are preferably bent into the shape shown, to space them apart a greater dis-

tance than the body engaging portion of the bar. These forwardly projecting bar portions have vertically aligned openings 18 through which pass the end portions of a 60 bearing tube 19, said tube having outwardly stamped circumferential shoulders 20 which contact with the inner sides of said bar ends. The extremities of this tube are swaged as at 21, into contact with the outer sides of the 65 bar end and by this construction and arrangement, the bars and the bearing tube are held in fixed relation.

The lower portion of the post 5 and the 70 ends 12 of the bars 11, are rotatably received in the tube 19 and the latter then rests upon the collar 15, so that an effective metal-to-metal bearing connection is provided between the steering post 5 and the body 6. To prevent downward movement of the post 75 with respect to the bearing or upward sliding of said bearing on the post, a screw 22 is preferably driven into said post to overlie the upper end of the sleeve 19.

It will be seen from the foregoing that 80 while the invention is simple and inexpensive and may be easily manufactured and applied, it will be durable and in every way desirable. Excellent results are obtainable from the exact details disclosed and I therefore prefer that they shall be followed. 85 However, within the scope of the invention as claimed, variations may be made.

I claim:

1. In a steering post mounting for a child's 90 vehicle; a post receiving metal tube having outwardly projecting shoulders near its ends, and a pair of metal bars having openings in one end receiving the ends of said tube, said bars contacting with said shoulders, said 95 ends of the tube being swaged against the outer sides of said metal bars to hold the latter and the tube in fixed assembled relation, said bars projecting from the tube for attachment to a body member of the vehicle. 100

2. In a steering post mounting for a child's vehicle; a pair of metal bars having transversely curved upper end portions secured to opposite sides of the steering post, said bars being directed outwardly and then 105 downwardly at the lower end of the post to provide a wheel-carrying fork, a collar surrounding said upper portions of said bars and resting on the outwardly directed portions of the latter, a bearing surrounding the 110 lower portion of the post, resting on said collar and engaging the transversely curved

upper portions of said bars, means for attaching said bearing to a body member of the vehicle, and post-carried means engaging the upper end of said bearing.

- 5 3. In a steering post mounting for a child's vehicle; a pair of metal bars having transversely curved upper end portions secured to opposite sides of the steering post, said bars being directed outwardly and then 10 downwardly at the lower end of the post to provide a wheel-carrying fork, a collar surrounding said upper portions of said bars

and resting on the outwardly directed portions of the latter, a bearing surrounding the lower portion of the post and the transversely curved portions of said bars, said bearing resting on said collar and having means for attachment to a body member of the vehicle, and means for holding the bearing against upward sliding on the bars and 15 post.

In testimony whereof I have hereunto affixed my signature.

ROMAN B. BUKOLT.
